JAMES O. MORSE, OF ENGLEWOOD, NEW JERSEY, AND GARDNER D. HISCOX, OF BROOKLYN, NEW YORK.

Letters Patent No. 96,607, dated November 9, 1869.

IMPROVEMENT IN STEAM-RADIATORS.

The Schedule referred to in these Letters Patent and making part of the same.

To all whom it may concern:

Be it known that we, JAMES O. MORSE, of Englewood, in the county of Bergen, and State of New Jersey, and GARDNER D. HISCOX, of Brooklyn, in the county of Kings, and State of New York, have invented a new and useful Improvement in Steam-Radiators; and we do hereby declare that the following is a full, clear, and exact description thereof, and of its mode or manner of operation, reference being had to the accompanying drawings, and to the letters of reference marked thereon, and making a part of this specification, in which—

Figure 1 is a transverse, and

Figure 2, a longitudinal vertical section, taken in each case through the centre line of one of the series or rows of tubes composing the radiator.

Our improvement relates to the construction of that class of radiators in which the steam circulates through a system of tubes arranged in pairs, one within the other.

The base of our improved radiator is a hollow chamber, A, of the usual form, from the upper plate of which rise the tubes E.

In one side or end of the chamber A is formed a compartment, B, by means of the diaphragm a.

In this diaphragm is inserted a series of horizontal tubes, C, closed at the inner end, and previously fitted to receive the upright inner tubes D, which are inserted through the openings left in the upper plate of the base A to receive the tubes E.

The tubes D are open at both ends; the tubes E only at the lower end.

These tubes, having been fixed in their places, if steam be let into the compartment B through the opening F, left for that purpose, it will take the course indicated by the arrows, filling first the series of tubes C, then the inner tubes D, from which it will overflow into the outer tubes E, and, finally, fill the main chamber A, expelling the air through the opening G.

The drip from the condensing steam in the chamber A and the tubes E will also escape through G.

That from the tubes D and C will pass through small openings, g, at the remote end of the tubes C, into the chamber A, and thence out through G.

These openings being made small, relative to the total area of section of the tubes C and D, are fully occupied by the passage through them of the drip from those tubes, and have no sensible tendency to divert the current of steam from its course through the tubes D and E.

If steam be taken in at G, the current will be re-

versed, and the opening for the final escape of the drip must be in the compartment B, in which case the openings g will be in the diaphragm a, instead of the tubes C.

The tubes B may be placed in their proper position in the mould before casting the base A, and the metal cast around them.

The arrangement of tubes for heating purposes in pairs, one within the other, in such a way that steam may pass from the inner tube to the annular space without it, or the contrary, has been long known and used, having been described and illustrated in works published thirty years ago, and upward; for example, in Peclet's "Traité de la Chaleur."

This arrangement in itself, therefore, we do not claim, but only those peculiarities of construction which distinguish our method of obtaining it from those previously in use.

As ordinarily constructed, the inner tubes D are inserted in a plate or sheet parallel with the upper plate of the base or chamber A, (or rather, with that in which the outer tubes E are inserted, which may be vertical or inclined at any angle, instead of horizontal, as here shown,) which thus divides the interior space into an upper and a lower, or a first and second chamber.

This method of construction gives a positive circulation of the steam, beginning in one of the two chambers and ending in the other, which it is desirable to retain.

It involves, however, certain mechanical difficulties in moulding and casting the chamber A, with its interior partition-plate, and in tapping into that plate the holes to receive the tubes D.

By giving an inconvenient and disproportionate height to the base, these difficulties may be in part obviated, but they are wholly avoided, without any such inconvenience, by the method which we have here described, of forming a lateral chamber, communicating with the inner tubes of the annular system, by means of tubes proceeding from and constituting an extension of it, in which the said tubes are inserted.

In this way, the process of moulding is simplified by removing the dividing-partition from the chamber A, leaving it comparatively shallow, while, at the same time, the positive circulation, due to the separation of the compartments A and B, is fully preserved.

As an improvement, therefore, in steam-radiators, composed of series of tubes arranged in pairs, one within the other, and opening into a hollow base,

We claim—

1. The diaphragm α , forming a separate compartment, at one side or end of the base.
2. The use of a separate compartment, formed at one end or side of the base, whether by means of the diaphragm or otherwise, and communicating with the innermost of the pairs of tubes composing the radiator, by means of a series of tubes proceeding from it,

in which tubes said inner tubes are inserted, substantially as described.

3. The small openings g , for the passage of the drip from the first to the second chamber.

JAMES O. MORSE.
GARDNER D. HISCOX.
